UNITED STATES PATENT OFFICE.

JERVIS R. HARBECK, OF CHICAGO, ILLINOIS, ASSIGNOR TO AMERICAN CAN COMPANY, OF NEW YORK, N. Y., A CORPORATION OF NEW JERSEY.

SHIPPING-CONTAINER.

1,185,903.

Specification of Letters Patent. Patented June 6, 1916.

Application filed June 1, 1914. Serial No. 842,274.

To all whom it may concern:

Be it known that I, JERVIS R. HARBECK, a citizen of the United States, residing in Chicago, in the county of Cook and State of Illinois, have invented a new and useful Improvement in Shipping-Containers, of which the following is a specification.

My invention relates in general to shipping containers for articles of various kinds and more particularly to containers provided for the packaging of small articles for shipment by parcels post, express and the like.

One of the principal objects of the invention is the provision of a container of the general character described in which the side or end, left open to receive the article or articles being shipped, may be closed without the use of glue or other permanent fastening means in order that the postal regulations covering the shipment of articles by parcels post may be complied with.

A further object of the invention is the provision of a container wherein the closure will be more tightly held in place when the weight of the article or articles carried in the container is felt thereby and wherein a relatively rigid closure may be employed without danger of damage to the contents of the container in transit.

Another object of the invention is the provision of a container which, while possessing the foregoing and numerous other advantages, will be cheap to construct, pleasing in appearance and efficient in use.

Other objects and advantages of the invention will be apparent as it is better understood from the following description considered in connection with the accompanying drawing illustrating a preferred embodiment thereof.

In the drawing, Figure 1 is a perspective view of a container embodying my invention closed and ready for shipment. Fig. 2 is a longitudinal sectional view taken substantially on the plane defined by the lines 2-2 in Fig. 1. Fig. 3 is a transverse sectional view taken substantially on the lines 3-3 of Fig. 2, and Fig. 4 is a diagrammatic view of a blank which may be employed in constructing the container shown in the other figures.

The container shown in the drawing consists of a rectangular body portion 5, each end of which is closed when the container is ready for shipment by a closure 6. The body portion 5 in the present instance is

made of corrugated cardboard from the blank shown in Fig. 4. This blank is scored on the lines 7 to form the four longitudinal walls 8, the adjoining edges of the blank being secured together along one corner by a strip 9 of paper, cloth or other suitable material. A flap 10 is provided at each end of each wall 8 and each of these flaps is slit or slotted at 11 for a purpose which will be hereinafter defined. The flaps 10 are bent at 12 and extend inwardly of the body portion of the container as seen in Fig. 2. These flaps are scored at 13 and bent toward each other inwardly of the scoring lines. The closure 6 is provided with oppositely and outwardly extending projections 14 adapted to enter into the slots 11 when the closure is positioned.

In practice the flaps at one end of the container are first turned inwardly and the closure 6 at this end positioned before the contents to be shipped in the container is packaged. The closure is moved inwardly from the end of the container until the projections 14 engage in the slots 11. The contents, generally designated at 15 in Fig. 2, is then inserted and the flaps 10 at the other end of the container are turned inwardly and the second closure 6 is positioned. The edges of the flaps or the portions located inwardly of the scored lines 13 are bent before the flaps are engaged by the closures to the angular positions shown in Fig. 2 so that the contents will rest upon these flaps when the container is placed on either end. These bent portions of the flaps perform the dual function of serving as a cushion to protect the contents at the end of the container and to tighten the engagement between the flaps and closures when the weight of the contents is sustained by an end. Under the pressure of this weight the flaps 10 leave the side walls of the container, consequently driving the projections 14 deeper into the slots 11.

It will be apparent that a container embodying my invention may be readily packed and closed for shipment, that it may be cheaply constructed, and that it will effectively protect its contents from damage. Since no adhesive or other permanent fastening means is necessary it complies with the requirements of the postal regulations.

It will be apparent that various changes may be made in the form and the construc-

tion of the container and of the closure without departing from the spirit and scope of the invention or sacrificing any of its material advantages, the form herein disclosed 5 being merely a preferred embodiment thereof.

I claim:

1. A shipping container having oppositely disposed, folded back and inwardly 10 extending flaps at its open side provided with slits in their adjacent faces, and a closure arranged between said flaps and pressing them to the walls of the container and provided with means for engaging said slits 15 to hold said closure in position, said flaps extending inward beyond the closure and pressing against the closure and its engaging means.

2. A shipping container having oppositely disposed, inwardly extending flaps 20 at its open side and a closure positioned between and held in place by said flaps and pressing the latter to the walls of the container, the edges of said flaps being bent 25 inwardly behind said closure into position to be engaged by the contents of the container to tighten the engagement between said flaps and said closure.

3. A shipping container having oppositely disposed, inwardly extending flaps 30 at its open side provided with the slits in their adjacent faces and a flat disk-like closure pressing the flaps to the walls of the container and provided with integral projections adapted to engage in said slits, said flaps extending inward beyond the closure.

4. A shipping container having oppositely disposed inwardly extending flaps of yielding material and a closure of relatively 40 stiff unyielding material positioned between and held in place by said flaps and partially embedded therein, the ends of said flaps being bent inwardly behind said closure to provide a yielding cushion for the contents 45 of said container.

5. A shipping container having at an open side flaps which are turned over from the walls of the container and extend within the latter, the extreme inner ends of said flaps 50 being bent away from the walls toward the center of the container, the said flaps being formed of yielding material; combined with

a closure positioned between the said flaps and pressing the same to the walls of the container, the said closure being located on 55 the flaps at points where the flaps are parallel with the walls of the container and outside of the lines at which their extreme inner ends are bent inward, and being partially embedded in the flaps.

6. A shipping container having at an open side flaps which are turned over from the walls of the container and extend within the latter, the extreme inner ends of said flaps being bent away from the walls toward 65 the center of the container, the said flaps being formed of yielding material, combined with a closure positioned between the said flaps at points outside of the inner ends thereof and pressing the same to the walls of 75 the container, the said closure being partially embedded in the bodies of the flaps.

7. A shipping container having at an open side flaps which are turned over from the walls of the container and extend within the 75 latter, the extreme inner ends of said flaps being bent away from the walls toward the center of the container, the said flaps being formed of yielding material and provided with slits 11 located at a distance outward 80 from the lines at which the extreme ends of the flaps are bent, combined with a closure positioned between the said flaps and pressing the same to the walls of the container, the said closure being located on the flaps 85 at points between the said slits and the lines at which the extreme ends of the flaps are bent inward.

8. A shipping container having at its open sides flaps which are bent inward from the 90 walls of the container and extend within the latter, the inner ends of said flaps being bent away from the walls of the container and toward the center thereof, and a closure within the said walls and flaps and arranged 95 on the flaps at the lines on which the inner ends of the flaps are bent.

Signed this 26th day of May, 1914, in the presence of two witnesses.

JERVIS R. HARBECK.
